(57) **CLAIM**

The ornamental design for a computer generated icon for a screen, as shown and described.

DESCRIPTION

The FIGURE is a front view of a computer generated icon for a screen showing my new design.

The broken lines shown in the drawing are for illustrative purposes only, and form no part of the claimed design.

1 Claim, 1 Drawing Sheet

UNITED STATES PATENT AND TRADEMARK OFFICE
CERTIFICATE OF CORRECTION

PATENT NO. : Des. 533,562 S
APPLICATION NO. : 29/228058
DATED : February 21, 2007
INVENTOR(S) : Bjorn Sundeb

Page 1 of 1

It is certified that error appears in the above-identified patent and that said Letters Patent is hereby corrected as shown below:

Title Page, Item (30)

Please replace the Foreign Application Priority Data with:

Oct. 20, 2004 (EU) 000241799-0001

Signed and Sealed this

Third Day of April, 2007

A handwritten signature in black ink, appearing to read "Jon W. Dudas". The signature is written in a cursive style with a large, stylized "D" and "u".
